UNITED STATES PATENT OFFICE.

DANIEL GALE TURNBULL, OF NEW YORK, N. Y., ASSIGNOR TO LEIGH POTTERS, INC., OF ALLIANCE, OHIO, A CORPORATION OF OHIO.

DESIGN FOR A PLATE OR SIMILAR ARTICLE.

Application filed February 21, 1929. Serial No. 30,167. Term of patent 3½ years.

To all whom it may concern:

Be it known that I, DANIEL GALE TURNBULL, a citizen of the United States, and resident of the borough of Manhattan, city, county, and State of New York, have invented a new, original, and ornamental Design for a Plate or Similar Article, of which the following is a specification, reference being had to the accompanying drawing, forming part hereof, which drawing is a face view of a plate or similar article illustrating my new design.

I claim:

The ornamental design for a plate or similar article, as shown.

DANIEL GALE TURNBULL.
